UNITED STATES PATENT OFFICE.

ALFRED HEALD, OF PHILADELPHIA, PENNSYLVANIA, ASSIGNOR TO McCALUM, CREASE & SLOAN, OF SAME PLACE.

DESIGN FOR CARPETS.

Specification forming part of Design No. 6,250, dated November 19, 1872.

To all whom it may concern:

Be it known that I, ALFRED HEALD, of Philadelphia, Pennsylvania, have invented a Design for a Carpet-Pattern, of which the following is a specification:

The main features of my design (which is fully represented in the accompanying drawing) are the three members or figures A, B, and C. The outlines of the figures A and B are precisely similar, each having a plain margin, *a*, partly straight and partly inclined, the general shape of the said figures approximating to that of a square, and the greatest inclines occurring at the corners where the said figures are cut away in order to provide sufficient space for the figure C, which is circular, or nearly circular. Each figure A contains a central ornament, *b*, and a waved ribbon, *d*, crossed by two diagonal bars, *e*, the space between the waved ribbon and the border being occupied by twigs *f*. The ornamentation of the figures B is of a more elaborate character, each having a lace-like border, *g*, following the shape of the outline *a*, and within

this border are central and corner ornaments of the character represented. A diagonal bar, *h*, crosses the figures B and C, and the latter is also crossed by a diagonal bar, *i*, at right angles to the bar *h*, and vanishing into the figures A. Diamond-shaped enlargements *j* occur upon the bars *h* and *i* in the space between the several figures, and this space, which may be considered the ground of the pattern, is occupied by foliated ornamentation of a character too clearly shown in the drawing to need description.

I claim—

The design for a carpet-pattern, substantially as described, and as illustrated in and by the accompanying drawing.

In testimony whereof I have signed my name to this specification in the presence of two subscribing witnesses.

ALFRED HEALD.

Witnesses:

Wm. A. STEEL,
HUBERT HOWSON.
